COMBINATION LEVELER-BENDER
Aubrey H. Hughes, 903 Weizmann,
San Antonio, Tex. 78213
Filed Oct. 8, 1965, Ser. No. 494,138
11 Claims. (Cl. 72—32)

ABSTRACT OF THE DISCLOSURE

Apparatus for suspending and leveling ceilings and the like including a liquid leveling device in combination with a wire bender, said leveling device comprising a liquid container with one end of a hose communicating therewith; the remote, closed end of said hose detachably connects to said wire bender whereby the user may work to a predetermined reference prior to activating said wire bender.

The present invention relates to a leveling device in combination with a wire bender and more particularly to such a combination leveler-bender for use in connection with the construction of suspended ceilings and the like.

At the present time, acoustic and lath and plaster ceilings are often suspended by means of a plurality of wires secured to the trusses or roof of a structure. The workman often encounters many difficulties in such type construction in that suspended ceilings not only must be level but also must be suspended to a predetermined height and the wires connecting thereto must provide adequate support for such suspended ceiling.

The present invention relates to a leveling device in combination with a wire bender whereby a workman may level such a suspended ceiling with a minimum of effort, work to a predetermined grade, and also properly secure such ceiling to the supporting structure.

An object of the present invention is the provision of a light weight leveling device which enables a workman to work to a predetermined grade or level line without many time consuming computations and measurements.

Another object is to provide such a leveling device in combination with a wire bender whereby each wire is bent uniformly and each bend is made at an exact, predetermined point.

A further object of the invention is the provision of a combination leveler-bender which enables a workman to level a workpiece and thereafter secure such workpiece in a suspended state with a minimum of effort.

Still another object is to provide such a combination leveler-bender which is inexpensive to manufacture, capable of mass production techniques, easy to use, and universal in its applicability.

Other objects and features of the invention will become apparent to those skilled in the art as the disclosure is made in the following detailed description of preferred embodiments of the invention as illustrated in the accompanying sheets of drawing in which:

FIG. 1 is a side elevational view, partly broken away and partly in section, of the leveling device of the subject invention.

FIG. 2 is a side elevational view, partly broken away and partly in section, of the wire bender used in combination with the leveling device of FIG. 1.

FIG. 3 is an enlarged, side elevational view, partly broken away and partly in section, of the lower portion of the container utilized in the embodiment of FIG. 1.

FIG. 4 is an enlarged, vertical sectional view through the float utilized in the embodiment of FIG. 1.

FIG. 5 is a front elevational view, partly broken away and partly in section, of the upper portion of the wire bender.

2

FIG. 6 is a rear elevational view of the wire bender of FIG. 5 wherein a wire, illustrated in reference lines, is bent by such device.

FIG. 7 is a side elevational view, partly broken away and partly in section, of the holding device utilized in the embodiment of FIG. 2.

FIG. 8 is a side elevational view showing the opposite side of the holding device, partly broken away, and attached to the wire bender.

Referring now to the drawings, wherein like reference characters designate like or corresponding parts throughout the several views, there is shown in FIG. 1 a leveling device 10 which in the preferred embodiment of the invention is used in combination with the wire bender 11 of FIG. 2. It is understood that leveling device 10 may be used independently of the wire bender 11 for general leveling purposes, and a modification of the wire bender, illustrated in FIGS. 5 and 6 of the drawings, may be used independently of the leveling device 10.

Leveling device 10 consists of a container 12 for water or other liquid, which container is composed of transparent material such as glass or clear plastic; a wide-mouthed jar including a screw thread on the upper portion thereof, such as a two quart mason jar, not only provides adequate capacity for the liquid required but also may easily be replaced in case of breakage of said container. In use, the container 12 is held in inverted position by means of a frame 13 or hanger 14, hereinafter to be described, whereby the said container may be detachably secured to a supporting structure 15.

Frame 13 consists of two identical, shaped members 16-17 of galvanized strap or the like, which members are positioned outwardly of the container and secured at their respective lower ends to a split ring 18. As shown in FIG. 3 of the drawings, each end of split ring 18 includes a perpendicularly outward extending eye 19-20; a bolt 21, carrying a washer 22, is passed through eye 20; a washer 23 is placed on such bolt outwardly of eye 19 and a nut 24 threaded on said bolt to draw the said ring firmly against the neck of the container. Prior to tightening ring 18 in such manner, container 12 is positioned in the frame 13, hereinafter to be described.

For purposes of convenience only, one half of member 16 will be described in detail, it is understood that the other half of such member 16 is a mirror image thereto and the member 17 is constructed in like manner. The lower terminal portion of each member 16-17, identified by 25, is passed in either direction around ring 18 or otherwise secured thereto; said member extends angularly outward and downward, indicated by 26, thence is turned vertically upward, indicated by 27, to pass outwardly of the container 12. Portion 27 extends to a point above the bottom of the container 12, after which the member is turned angularly downward and inward, indicated by 28, and thence bent horizontally, indicated by 29, along the bottom of the container. The horizontal portions of members 16, 17 are crossed and hanger 14, heretofore mentioned, is secured thereto. A pear-shaped aperture 30 is provided in portion 27 of each member 16, 17 above the bottom of container 12 to accommodate the head of nail 31 or the like inserted into the supporting structure 15.

Hanger 14, composed of galvanized rod or the like, as best seen in FIG. 1 of the drawings, consists of base 32 and converging legs 33-34 integrally formed therewith. The horizontal portion 35 of member 17, corresponding to portion 29 of member 16, is passed over base 32 of the hanger and a rivet 36 or the like is passed through the crossed members 16, 17 on each side of base 32 and expanded. Such hanger may be used for carrying the

leveling device 10 or securing the same from any horizontal support.

As illustrated in FIG. 3 of the drawings, container 12 includes a screw thread 37 adapted to receive a flanged-screw ring 38 and cover 39 positioned therein. More particularly, cover 39 includes a depression 40 in the upper surface around the periphery thereof which accommodates a gasket 41 or the like. Such gasket bears against the annular rim of container 12 when the cover is properly positioned in such flanged ring 38 to form a leak-proof seal.

Cover 39 includes a bore 42 inwardly of the depression 40 in which bore is secured a vertical tube 43 as by soldering or the like. The lower end of tube 43 extends slightly below the lower surface of the cover and a fillet, indicated by 44, provided in the angle thus formed. One end of a flexible hose 45 is placed on the upstanding portion of tube 43 in a friction fit while the other end of said hose 45 is attached to a float 46.

There is shown in FIG. 4 of the drawings the light weight float 46, composed of expanded polystyrene or the like, which float includes a central, vertical bore 47. A tube passes through said bore, the upper end of said tube 48 terminates at the upper surface of the float while the lower end of said tube extends downwardly of the lower surface of said float and the other end of hose 45 fits thereon in a friction fit. An annular cap 49, including a downturned peripheral edge 50, is centered and secured to the top of said float by means of a plurality of downwardly depending tines 51 integral with edge 50; a slight gap is maintained between the lower rim of edge 50 and the top of the float in order that air may enter into the container. If required, an annular weight 52 (see FIG. 1) may be crimped or otherwise secured to hose 45 slightly below the float and aids in maintaining the float upright. It is evident that cap 49, in combination with weight 52, prevents water from entering into the air vent thus formed.

Referring again to FIG. 3 of the drawings, bore 53 is provided in cover 39 inwardly of depression 40; vertical tube 54 is secured therein in a conventional manner with the upper end extending slightly above the upper surface of cover 39 and a fillet, indicated by 55, provided in the angle thus formed. The lower end of tube 54 extends downwardly of the lower surface of cover 39 and a flexible hose 56, preferably of clear plastic, fits thereon in tight fitting relationship. One end of a coil spring 57 is forced over such connection until stopped by the lower surface of cover 39, which spring 57 aids in preventing crimping or damage to hose 56 in proximity to such connection. As best seen in FIG. 2, the other end of hose 56 is provided with a stopper 58, such as is well known in the art, whereby air may be bled from hose 56.

There is shown in FIG. 2 of the drawings the wire bender 11 and its associated apparatus which is used in combination with the leveling device 10 of FIG. 1; however, for purposes of convenience, the basic structure of the wire bender, illustrated in FIGS. 5 and 6, will first be described. It is obvious that such wire bender, hereinafter to be identified by reference numeral 59, may be used independently of the leveling device 10 for general wire bending operations.

Wire bender 59 consists, in general, of handles 60-61, front plate 62 intermediate plate 63, rear plate 64, link 65, and arm 66, respectively. As best seen in FIG. 2 of the drawings, handle 61 is preferably shaped to conform to the hand of the user, such handle is generally inverted U-shape in section. The upper, downwardly depending sides 67 of handle 61 pass laterally of the flat, vertically aligned and longitudinally extending intermediate plate 63 and the foremost ends of such sides preferably abut the rearmost, vertically extending ends of plates 62, 64 as shown in FIGS. 2 and 6. Bolt 68

or other conventional securing means is passed through aligned bores (not shown) in the sides 67 and intermediate plate 63 and a nut 69 is threaded thereon.

Handle 60 is inverted, U-shape in section and as illustrated in FIG. 5, such handle includes a slot 70 adjacent the upper end thereof; sides 71 of handle 60 extend laterally of the sides 67 of handle 61 and pivotally connect thereto as by means of bolt 72 passing through an aligned bore (not shown) in sides 71, 67 and the intermediate plate 63 with a nut 73 threaded onto said bolt 72.

As illustrated in FIG. 2, front plate 62 is rectangular in elevation, the minor axis of which is parallel to the longitudinal axis of the device. Plate 62 includes a transversely extending flange 74 (see FIGS. 5 and 6) which terminates at the outer surface of rear plate 64. Spaced, vertically aligned slots 75 in the top and bottom surfaces of plate 62 accommodate the holder 76 of FIG. 7.

Referring again to FIGS. 5 and 6 of the drawings, the rear plate 64 terminates forwardly in a transversely extending, vertically aligned flange 77; the foremost end of intermediate plate 63 abuts the inner surface of flange 77, while the end of such flange 77 abuts the inner surface of front plate 62. A vertically extending channel, indicated generally by 78, is provided between the rearmost surface of flange 74 and the foremost surface of flange 77, respectively, and accommodates a wire 79 which is to be bent at a desired, predetermined point. Spaced, machine screws 80-81 hold the plates 62-64 in such arrangement.

Arm 66 is pivotally connected to the lower, medial part of rear plate 64 as by a bolt 82 or the like with a nut 83 threaded thereon; one end of link 65 connects to the sides 71 of handle 60 by means of bolt 84 and nut 85 threaded thereon (see FIG. 2), while the other end of such link connects to the upper, outer side of arm 66 by means of a machine screw 86 with an annular spacer 87 (see FIG. 8) placed on said screw between link 65 and arm 66, respectively. A spring 88 passes through slot 70, one end of said spring connects to bolt 84 while the other end of said spring connects to machine screw 89 which passes through plates 64 and 62; spring 88 maintains the handles 60, 61 separated preparatory to a bending operation.

A perpendicularly outward extending tab 90 is integral with the lower end of plate 64 and serves as a stop for arm 66 when such arm is essentially vertical, as illustrated in FIG. 5. Referring to FIGS. 2 and 8 of the drawings, arm 66 further includes an integrally formed, transversely extending base 91 and terminal portion 92 perpendicular thereto which portion 92 passes outwardly of the front plate 62. A V-shaped recess 93 is provided in the upper end of base 91 and an inverted V-shaped recess 94 in the lower end of flange 74, which recesses aid in positioning wire 79 and bending the same.

There is shown in FIGS. 7 and 8 the holder 76 which is detachably connected to the wire bender 59 of FIGS. 5 and 6 of the drawings. More particularly, such holder is formed of channel or the like and includes integrally formed male connectors 95 which insert into the slots 75 in plate 62. An L-shaped locking device 96 pivotally connects to a cross piece 97 (see FIG. 7) by means of bolt 98 and nut 99 threaded thereon, said locking device may be rotated to pass behind the upper, rear surface of the front plate 62 thereby detachably securing such holder to the wire bender. A tape 100 or other measuring device is secured to the web of such channel as by rivets 101 or the like. Additionally, U-shaped fastening means 102 are fixedly secured in proximity to the upper and lower ends of holder 76 in which hose 56 is detachably secured to the wire bender, as best seen in FIG. 2.

Prior to use, hose 56 is completely filled with liquid from container 12 and all air bled therefrom by first removing stopper 58 from the end of said hose and then elevating leveling device 10 above said hose. Leveling device 10 is then secured to the supporting structure 15

by means of nail 31 passing through aperture 30 so that the water level in container 12 is at the desired grade. It is obvious that when the stopper 58 is removed from the hose, the water or other liquid in said hose seeks the level of the liquid in container 12 and the meniscus of such liquid in hose 56 indicates the desired grade; wire bender 11 is raised or lowered until the proper point for bending wire 79, as indicated on tape 100, is located. A compressive force applied to handles 60, 61 of the wire bender causes arm 66 to pivot upwardly and the free end of wire 79, positioned in channel 78 and secured and guided by recesses 93, 94 is bent upwardly about the lower end of flange 74 and assumes a U-shape, as viewed from the side (see FIG. 6). Stopper 58 is replaced after each such bending operation to prevent accidental loss of water or other liquid in the event that wire bender 11 is below container 12. When hose 56 is not in use, the said hose may be coiled and placed over portion 28 of frame 13.

It should be understood, of course, that the foregoing disclosure relates to only preferred embodiments of the invention and that numerous modifications or alterations may be made therein without departing from the spirit and scope of the invention as set forth in the appended claims.

What is claimed is:

1. In combination, a leveling device and a wire bender, said leveling device consisting of a container and a frame, holding means on said wire bender, and a hose connected to said container and said holding means.

2. In combination, a liquid leveling device and a wire bender, said leveling device consisting of a container and a frame, said frame passing outwardly of said container, holding means on said wire bender, and a transparent hose connected to said container and said holding means.

3. In combination, a leveling device and a wire bender, said leveling device consisting of a transparent container and a frame, said frame passing outwardly of said container and supporting said container, venting means in said container, holding means detachably connected to said wire bender, an elongate transparent hose connected to said container and detachably connected to said holding means.

4. In combination, a leveling device and a wire bender, said leveling device consisting of a container and a frame, said frame passing outwardly of said container and securing said container, means to support said frame in elevated condition, venting means communicating with said container, holding means on said wire bender, and a transparent hose connected to said container and detachably connected to said holding means on said wire bender.

5. A liquid leveling device comprising a transparent container including a screw thread, a flanged ring screwed onto said thread, a cover supported by said flanged ring, first and second tubes passing through said cover, one end of a hose connected to the end of said first tube extending into said container, the other end of said hose connected

to a float, an elongate transparent hose connected to the end of said second tube extending outwardly of said container, means to restrict the flow of liquid in said transparent hose, and a frame passing outwardly of said container and supporting said container.

6. The invention of claim 5 including means secured to said float to prevent liquid from entering into said hose.

7. The invention of claim 5 including means secured to said hose to maintain said float in vertical alignment.

8. A wire bender consisting of an intermediate plate, a front plate and a rear plate, said plates connected together, said front plate having a flange extending transversely rearward, said rear plate having a flange extending transversely forward, a channel between said flanges, a first handle secured to said intermediate plate, a second handle pivotally secured to said first handle, an arm pivotally connected to said rear plate, and a link connected to said arm and said second handle.

9. The invention of claim 8 including holding means on said front plate.

10. The invention of claim 8 including holding means detachably secured to said front plate.

11. In combination, a leveling device and a wire bender, said leveling device consisting of a transparent container including a screw thread, a flanged ring screwed onto said thread, a cover supported by said flanged ring, first and second tubes passing through said cover, one end of a hose connected to the end of said first tube extending into said container, the other end of said hose connected to a float, one end of an elongate transparent hose connected to the end of said first tube extending into said container, means restricting the flow of liquid in said transparent hose, a frame passing outwardly of said container and securing the same, said wire bender consisting of an intermediate plate, a front plate and a rear plate, said plates connected together, said front plate having a transversely rearward extending flange, said rear plate having a transversely forward extending flange, a channel between said flanges, a first handle secured to said intermediate plate, a second handle pivotally secured to said first handle, an arm pivotally connected to said rear plate, and a link connected to said arm and said second handle, holding means detachably connected to said front plate, the other end of said transparent hose detachably connected to said holding means.
